Primary Examiner — Richard Kearney

(57) **CLAIM**

The ornamental design for a hanging lamp for a display screen, as shown and described.

DESCRIPTION

1. Hanging lamp for a display screen

1.1 : Front

1.2 : Back

1.3 : Left

1.4 : Right

1.5 : Top

1.6 : Bottom

1.7 : Perspective view 1

1.8 : Perspective view 2

(Continued)

The product incorporating the design is used for illumination; the drawing designated to best show the essential features of the design is the perspective view 1.

1 Claim, 8 Drawing Sheets
